UNITED STATES PATENT OFFICE.

JAMES SMITH LANIER, OF CHAMBERS COUNTY, ALABAMA.

QUILL-CLEANER.

1,190,919.

Specification of Letters Patent.

Patented July 11, 1916.

Application filed August 21, 1913. Serial No. 786,024.

To all whom it may concern:

Be it known that I, JAMES SMITH LANIER, a citizen of the United States, residing in the county of Chambers and State of Alabama, have invented certain new and useful Improvements in Quill-Cleaners; and I do hereby declare the following to be a full, clear, and exact description of the invention, such as will enable others skilled in the art 10 to which it appertains to make and use the same.

This invention relates to improvements in the art of removing waste yarn from quills or bobbins, and more particularly to means 15 for feeding quills to yarn removing means and also to pneumatic means for removing the yarn.

In the accompanying drawing, Figure 1 is a view partly in vertical section and 20 partly in elevation embodying the features of the present invention. Fig. 2 is a top plan view thereof, parts being seen in horizontal section. Fig. 3 is a transverse section taken on the plane indicated by line 25 3—3 of Fig. 2.

Referring to the drawing by numerals, 1 indicates a pneumatic tube through which is passed a cleansing blast from any appropriate source, as a fan, blower or pump, not 30 illustrated, or a compressed air tank 2. Extending through the tube 1 are rods 3, 3 which are spaced apart appropriately for forming a series of tracks for quills, the rods being spaced a distance less than the 35 diameter of the heads of the quills but greater than the bodies of the quills and the waste carried thereby. The several rods 3 are arranged on an incline and those portions of the rods which extend upwardly 40 from the tube 1 are surrounded by a pan or casing 4 formed merely of confining vertical walls adapted to prevent unguided quills from rolling or otherwise falling from the tracks 3. Adjacent the upper ends of the rods 3 45 said rods are connected by a cross bar 5 which is engaged by a connecting rod or pitman 6, the latter in turn engaging a strap 7 of an eccentric 8 fixed to a power shaft 9. The shaft 9 is driven from any source not illustrated and is adapted to rotate sufficiently 50 rapidly to impart a rapid vibratory movement to all of the rods or tracks 3, the movement being preferably comparatively short

in the length of stroke. Disposed above the upper end portions of rods 3 is a hopper 10 55 whose lower end opens within the casing 4 immediately above the rods 3, a sufficient space being left for the free discharge of quills from the hopper 10 onto the rods. An appropriate container 11 for waste is 60 preferably disposed beneath the lower end of the tube 1.

The casing 4 and rods 3 are preferably fixed to the tube 1 and the tube 1 is formed in its side walls with slots appropriate for 65 admitting the passage of quills, the slots being disposed to register with the spaces between the rods. As the said rods are fixed to the tube 1, and the tube is fixedly supported by any appropriate frame or 70 other sustaining means not illustrated, the movement of the upper ends of rods 3 by the vibrating device is accomplished by the springing of the rods so that the vibration is rendered very effective. Obviously, numerous other forms of apparatus might be 75 adopted for effecting the vibration and the tracks for the quills might be otherwise mounted.

In operation, the blast being turned on, as 80 by opening a valve 12, the hopper 10 is filled with quills taken from shuttles or other sources and bearing varying portions of waste yarn, such for instance, as the quills discharged from automatic looms. 85 The quills are deposited on the rods in a more or less confused state as to relative disposition, but the vibratory movement causes those quills which do not first fall into a pendent position to become aligned 90 with the slots or openings between the rods and thereupon the tapered or smaller end of each quill drops down and the respective quill thus hangs by its head resting on two adjacent rods with the body of the quill 95 pendent between the rods. The incline of the rods should be sufficient to insure travel of the quills longitudinally of the rods by gravity, and this will, of course, be enhanced by the vibratory movements of the 100 rods. As the quills move through the respective slots in the walls of tube 1 and thus enter the line of blast, the ends of the 105 yarn are picked up by the blast and the remaining yarn is blown off rapidly down into the container 4 where it falls in a

loosened mass, and from which it may be subsequently removed either for use as waste or for being treated for returning it to its initial fibrous condition, or otherwise disposed of.

It will thus be observed that the apparatus as above set forth is adapted to automatically feed and clean quills, and I find this automatic action very effective where the quantity of waste yarn for the several quills is about uniform, but I have observed that where the "feelers" of pneumatic looms either get out of adjustment or have not been properly adjusted the quantity of yarn left as waste on various quills varies considerably and sometimes almost a full bobbin or quill will appear with the quills to be cleaned. Such full quills, being thicker through the winding than at their heads will not fall through the slots or openings between the rods or tracks 3, but such quills will roll or otherwise find their way down the tracks within the casing 4 until they lodge against the tube 1. If allowed to remain, a few of such quills would clog the operation which, of course, would do no further harm than to discontinue momentarily the cleaning of quills. This can be overcome by an operator picking out two full quills, or if any other quills happen to find their way entirely down to the tube 1 without assuming the pendent position the operator can readily adjust such quills into

the slots and thus allow the cleaning operation to continue.

35

What I claim is:

1. In a quill cleaner, the combination of a pneumatic tube, and a track extending through the tube and adapted to sustain a quill while waste yarn is being pneumati- 40 cally cleaned from the quill.
2. In a quill cleaner, the combination of a pneumatic tube, and a track extending through the tube on an incline sufficient for causing a quill to travel through the tube 45 on the track by gravity for subjecting the quill to the removal of waste yarn pneumatically while in the tube.
3. In a quill cleaner, the combination of pneumatic cleaning means for removing 50 waste yarn from quills, a track for delivering quills to said cleaning means, and means for vibrating the track.
4. In a quill cleaner, the combination of pneumatic cleaning means for removing 55 waste yarn from quills, a track for delivering quills to said cleaning means, means for vibrating the track, and means for delivering quills to the track.

In testimony whereof I affix my signature 60 in presence of two witnesses.

JAMES SMITH LANIER.
